(57) **CLAIM**

The ornamental design for the handle for garden tool, as shown and described.

DESCRIPTION

FIG. 1 is a perspective view of a handle for garden tool showing my new design;

FIG. 2 is a top elevational view thereof;

FIG. 3 is a bottom elevational view thereof;

FIG. 4 is a right side elevational view thereof;

FIG. 5 is a left side elevational view thereof;

FIG. 6 is a front elevational view thereof;

FIG. 7 is a front elevational view of FIG. 1 with the broken line removed for clarity; and,

FIG. 8 is a rear elevational view thereof.

The front portion of the garden tool is shown in broken lines for illustrative purposes only and forms no part of the claimed design.
